Julius E. Hansen, Providence, R. I.

Application September 15, 1949, Serial No. 5,015

Term of patent 3½ years

(Cl. D57—6)

To all whom it may concern:

Be it known that I, Julius E. Hansen, a citizen of the United States, residing at 1180 Narragansett Boulevard, Providence, county of Providence, State of Rhode Island, have invented a new, original, and ornamental Design for a Goggle, of which the following is a specification, reference being had to the accompanying drawings, forming a part thereof.

In the drawings, Fig. 1 is a front perspective view of a goggle showing the essential features of my new design in full lines; Fig. 2 is a view in rear elevation, the temples being omitted in this view for clarity; and Fig. 3 is a fragmentary sectional view taken on the line 3—3 of Fig. 2.

I claim:

The ornamental design for a goggle, substantially as shown and described.

JULIUS E. HANSEN.
